UNITED STATES PATENT OFFICE

CHARLES POKORA, OF MILWAUKEE, WISCONSIN

INDICATING DEVICE

Application filed November 5, 1928. Serial No. 317,440.

This invention relates to improvements in indicating devices.

It is one of the objects of this invention to provide an improved indicating device, particularly adapted for use upon typewriters which is provided with means for automatically sounding a warning when the bottom of the sheet is being approached.

It is a further object of this invention to provide a device of the class described in which cam means engageable with a platen of the typewriter is provided for simultaneously sounding the warning at the proper time and for resetting the device in readiness for the next sheet of paper.

It is a further object of this invention to provide an indicating device which may be readily adapted for use upon any of the standard makes of typewriters.

A further object of this invention is to provide an indicating device having adjustment means for varying the distance from the bottom of the sheet at which the warning will be sounded.

A more specific object of this invention is to provide an indicating device in which a roller on the end of a feeler and detector arm, normally resting upon the sheet of paper, is adapted to drop into a recess when the end of the sheet is reached, the said movement of the arm in dropping into the recess, operating to release a draw rod and to cause a gong operating and resetting cam to engage the platen of the typewriter.

A further object of this invention is to provide a device of the class described in which the feeler arm may be held in inoperative position when desired, and in which the entire device may be readily moved to an out-of-the-way position on the typewriter when its use is not necessary.

A further object of this invention is to provide an indicating device in which the feeler arm and its mechanism are provided with a guard which serves as a casing, as a guide for the sheet both above and below, and as a means for lifting the feeler arm.

It is a further object of this invention to provide a device of the class described which

is compact in form, efficient in operation, and well adapted for the purpose described.

With the above and other objects in view, the invention consists of the improved indicating device, and all its parts and combinations as set forth in the claims and all equivalents thereof.

In the accompanying drawings in which the same reference characters designate the same parts in all of the views:

Fig. 1 is a plan view of a portion of a typewriter with the improved indicating device in attachment therewith;

Fig. 2 is an enlarged sectional view taken on line 2—2 of Fig. 1;

Fig. 3 is a detail view showing the means for connecting the end of the gong to the device;

Fig. 4 is an enlarged sectional view taken on line 4—4 of Fig. 1;

Fig. 5 is an enlarged detail view showing the adjustable securing means for the end of the spring;

Fig. 6 is an enlarged detail view of the feeler arm guard;

Fig. 7 is a view similar to Fig. 2 showing the cam in a position of engagement with the platen, the dotted lines indicating various operating positions of the parts;

Fig. 8 is a fragmentary view of a portion of the mechanism shown in Fig. 7;

Fig. 9 is a view similar to Fig. 8 showing the position of the parts when the cam is in a platen engaging position;

Fig. 10 is a sectional view taken on line 10—10 of Fig. 2;

Fig. 11 is a detail, broken away view, showing the draw rod adjustment;

Fig. 12 is a sectional view taken on line 12—12 of Fig. 11;

Fig. 13 is a side view showing a modified form of indicating device;

Fig. 14 is a detail, broken away view illustrating a modified form of bracket;

Fig. 15 is a detail view of a portion of the gong hammer arm; and

Fig. 16 is a detail view of the rear of the modified form of bracket shown in Fig. 14.

Referring to the drawings, the numeral 15 designates a portion of a typewriter, and the

numeral 16 the platen rotatably mounted therein. Secured to the sides of the typewriter are special brackets 17 having upstanding portions 18, between which a rod 19 for carrying roller arms 20 extends. The said special brackets are necessary in order to position the rod 19 sufficiently forward on the platen so that it will not interfere with the indicating device.

10 The back plate or rear paper table 21 of the typewriter is preferably constructed with an offset portion 22, to allow the sheet of paper, when it is reversed, to pass over the plate of the indicating device instead of slipping beneath the same.

15 Brackets 23 and 24 for supporting a rod 25, extend rearwardly from the sides of the typewriter. The bracket 24 is offset to the left to provide a space on the rod 25 at the left 20 of the machine, to which the indicating device may be moved when it is not in use. The rod 25 is formed with a longitudinal groove 25' therein.

25 The frame of the indicating device proper is angular in shape, and comprises a side portion 26, and lower supporting plate 27. Both of the portions 26 and 27 project downwardly in the rear, as at 28 and 29 respectively. Secured to the depending position 29 is a 30 bracket 30 having a pair of outwardly extending portions 31 formed with openings 32. Within the latter openings, the rod 25 of the typewriter is adapted to extend to secure the device to the typewriter. The openings 32 35 have slots 33 extending rearwardly therefrom (see Fig. 14). Extending between these slots is a small rod 34 which is forced into the groove 25' of the typewriter rod 25 by a band spring 35 to yieldingly hold the device 40 against rotation upon the rod 25.

45 If it is desired to swing the device upwardly on the rod, the spring 35 will give, and permit the small rod 34 to disengage the groove 25'. Lateral movement of the indicating device, to properly position it for various widths of paper, is permitted by the longitudinal groove 25'.

50 In the modified form of bracket illustrated in Fig. 14, the bracket has screws 36 extending therefrom which extend through oval openings 36' in the portion 29 of the frame of the device. Nuts 37 are threaded on the screws on each side of the frame portion 29, and by adjusting the latter, the indicating 55 device may be positioned properly with relation to the platen. This feature is very advantageous in that it permits the use of the device on various makes of typewriters, as it may be readily adjusted to each particular 60 machine. The oval openings 36' permit raising and lowering the device.

65 Referring to Figs. 2, 7, 8 and 9, the side portion 26 is formed with a longitudinally and obliquely extending slot 38 with which 65 a rectangular recess 39, extending down-

wardly from the upper edge of the device, communicates. Extending inwardly from the side 26, above the slot 38, is a recess 40.

Within the recess 38 is a slidable draw rod 41, having an outer end 42 of diminished size, 70 forming the male portion of the draw rod (see Fig. 11). The said male portion is formed with a plurality of perforations 43. The male portion of the draw rod fits within an opening 44, in a female portion 45. The 75 said female portion has an upwardly extending portion 46 positioned within the opening 39 of the frame, formed with a vertical opening 47 communicating with the opening 44. The opening 47 has its lower portion of less diameter than the upper portion, forming a shoulder 48 within the opening. The upper end of the portion 46 is formed with a cut away portion leaving a projection 49. A locking member 50, having a knurled head 51, and having a coil spring 52, attached thereto and surrounding its medial portion, fits within the opening 47, the lower end of the coil spring resting on the shoulder 48 of the opening. The locking member is further 90 formed, near its upper end, with a lug 53 projecting laterally therefrom. Downward pressure upon the locking member will cause its lower end to engage one of the perforations 43 in the male portion of the draw rod 95 to lock the female portion thereto. By turning the locking member, the lug 53 will slip beneath the projection 49 and hold the locking member in position (see Fig. 12). By having the locking member engage different 100 perforations in the male portion of the draw rod, the length of the latter may be varied for a purpose to be hereinafter pointed out.

Near the inner end of the draw rod is a rod 105 54 extending outwardly therefrom, and carrying a pivotally mounted cam or operating member 55. The said cam has a strip of rubber 56 extending around its outer edge, and also has a weight 57 in its lower portion. Also pivotally connected to the draw rod is 110 a member 58 (see Figs. 8 and 9) having an enlarged lower portion 59 formed with a groove 60. The upper end of the member 58 is formed with an extension 61 and with a lug 62. A stop member 63 is provided adjacent the member 58. Toward the middle of the draw rod is a finger 64, extending obliquely therefrom and having an inwardly bent end portion which is adapted to engage the groove 60 in the member 58, as shown in Figs. 115 7 and 9. A bell-lever tripping lug 65 is secured to the female portion of the draw rod. Within the recess 40, in the side 26, is a 120 pivoted cam member 66, formed with a recess 67 in its lower side, and engaged by a spring 68. The recess 67 is adapted to receive a lug 69 extending from the draw rod to hold the latter rod in "set" position. Pivoted to the side 26, on a shaft 70, adjacent the recess 40 125 and partially covering the same, is an outer

cam 70'. The said cam has a pin 71 extending into the recess and engaging the end of the cam 66 to trip the same.

Rigidly secured to the outer side of the cam 70' is an angular shaped member 72, the lower end of which is adapted to engage the projection 62 on the member 58, to free said member from the finger 64 and to allow it to fall to the position shown in Figs. 2 and 8. A spring 73, having one end connected to the frame and positioned within a recess 74 (see Fig. 10) has its other end secured to the draw rod. The end of the cam 70' is adapted to engage a member 75 (see Fig. 10) which is pivoted to the side portion 26, to disengage the cam 55 at its lowest point from the platen when the latter is reversed.

A gong hammer 76, which is pivoted to the frame above the draw rod, is engaged by a spring 77. A projecting member 78, which pivots outwardly from the hammer has one side formed with an inwardly extending bevel 78', and has its outer edge engaged by a spring 79. The straight side of the member 78 is adapted to be engaged by the projection 65 when the draw rod is being moved in a direction away from the platen, to raise the hammer, as shown in Fig. 7, to cause a gong 80 to be sounded. When the draw rod springs back toward the platen, the projection 65 will engage the bevel on the member 78 and cause the same to pivot to permit the lug 65 to pass.

The gong 80 is formed by a coil of wire having one end secured to an extension 81 from the side 26. The said extension is integral with a section of metal which is set in the frame as shown in Fig. 3, and which is separated from the frame proper by a section of babbitt 82, the latter lending a clearer tone to the gong.

Referring to Figs. 4 and 6, which illustrate the other side of the device, it will be seen that the shaft 70, upon which the cam 70' is mounted, is journaled through the frame, and is bent around on the other side to form an arm 83. A hub portion 84 surrounds said arm adjacent the frame. A spring 85 is coiled about the hub and has one end engaging the arm to normally hold it in a down position. The other end of the spring is formed with a head 86, which is adapted to fit in one of the openings 87 as shown in Fig. 5. By employing different openings, the tension of the spring may be varied. The lower end 88 of the arm, is bifurcated to receive a rotatably mounted roller 89. The roller 89 is adapted to fit within a recess 90 in the frame portion 21.

A housing 91 for the arm 83 comprises a pair of plates 92 and 93 having curved ends which are hinged together as at 94 to hold the plates in spaced apart relation. The plate 93 has one edge bent upwardly to form a side piece 95. The said side piece is pro-

vided with an oval opening 96 through which the shaft 70 extends. A spring member 97, having its free end engaging the hub 84, holds the housing in a forward position.

Rotatably mounted between the side piece 95 of the housing and an extension 98, is a roller 99 provided with a ratchet wheel 100. The said ratchet wheel is adapted to be engaged by dogs 101 and 102, the said dogs being held yieldingly by springs 103 and 104. The dog 102 is provided with an extension 105 engaging a pin 106 projecting from the side of the frame. The plate 95 is also formed with a recess 107 (see Fig. 6) which is adapted to engage the pin 106 when the housing 91 is pushed rearwardly against the tension of the spring 97, to maintain the housing in said rearward position.

The side of the device shown in Fig. 2 may be provided with a suitable housing (not shown) to protect the parts.

In the modified form of device illustrated in Fig. 13 the majority of the parts are similar to those in the principal form. The locking member 50, however, extends from the female portion of the draw rod on the outside of the frame. Said member is formed with a lower end 50' which has a rectangular opening through which the male portion of the draw rod extends. The said male portion 50 is formed with a plurality of notches 43, which are adapted to be selectively engaged by the lower end of the locking member 50 to adjust the length of the draw rod.

A further difference in the modified form resides in the substitution of a bell 80 in place of the gong. The said bell is adapted to be engaged by a hammer 76 mounted on a member 76' pivoted to the frame. The member 76' is provided with a projection 76'' and with a pivoted dog 76'''. Pivoted to the frame above the member 76' is an arm 80' having ratchet teeth on its lower end. When the arm 80' is moved by reason of the pin 65 on the draw rod engaging a projection on its upper end, on the back stroke of said arm 80' the ratchet teeth engage the dog 76''' and cause the member 76 to vibrate up and down ringing the bell. The said bell construction gives a sustained ring which may be easily differentiated from the bell now on typewriters for indicating the end of a line.

The operation of the device is as follows:

The sheet of paper to be written upon is placed in the machine as shown in Fig. 1, the paper passing beneath the roller 89 on the arm 83. The various parts of the device are in the positions shown in Fig. 2, with the exception of the fact that the finger 64 is in engagement with the member 58. The roller 89 is raised slightly above the paper because of the fact that the finger 64 being in engagement with the member 58 causes said member to hold the cam 70' in a raised position (see Fig. 7), the cam in turn, through the shaft 70

70 holding the roller carrying arm 83 on the other side of the device up.

The next step is to retract the platen of the typewriter a few notches. In so doing, the 5 platen engages the roller 99 (see Fig. 4), and in view of the fact that said roller is held against rotation because of the dog 101 engaging the ratchet 100, the roller 99 and the guard, are raised upwardly, the lower plate 93 of the 10 guard raising the arm 83 and roller 89. This in turn raises the cam 70' on the other side of the device causing the end of the member 72 to engage the projection 62 on the member 58, to disengage the latter from the finger 64. 15 The member 58 will then drop from the position shown in Fig. 9 to the position shown in Fig. 8, and upon turning the platen in a forward direction, the roller 99 and guard 95 will be lowered, the roller being held against 20 rotation by the engagement of the dog 102 engaging the ratchet 100 until the end of the dog is raised by engagement with the pin 106. During this operation the cam 70 is permitted to fall slightly and the arm 83 and roller 89 to 25 fall and engage the paper. The only thing preventing the cam 70' from dropping further is the fact that the paper prevents the roller 89 and arm 83 from dropping into the recess 90, and as the cam 70' and arm 83 are 30 both rigidly secured to the shaft 70, movement of the cam 70' is dependent upon movement of the roller arm 83 and vice versa.

When the portion of the paper upon which the typing is being done is within 2 1/2, 2, 1 1/2, 35 1, or 1/2 inch from the bottom of the sheet, according to the adjustment of draw rod, the bottom of the sheet will clear the roller 89 and allow it to fall into the recess 90 as shown by the dotted lines in Fig. 4. This movement 40 of the roller 89 causes the cam 70' on the other side to drop. In so doing, the pin 71, extending inwardly from the cam engages the small cam 66 within the recess 40, and causes the cam to pivot so that the projection 69 on the 45 draw rod is released from the recess 67 in the cam 66. This allows the spring 73 to pull the draw rod from the position shown in Fig. 2 to the position shown in Fig. 7, the cam 55 engaging the platen of the typewriter. Upon 50 further rotation of the platen, as the typist progresses, the cam will ride on the platen and rotate on its pivot as shown by the dotted lines in Fig. 7. This will cause the draw rod to be forced rearwardly against the tension of the spring 73, and it will cause the lug 65 on the draw rod to engage the member 78 on the bell hammer arm 76 to trip said hammer arm, as shown by the dotted lines in Fig. 7, resulting 55 in the sounding of the gong. The gong will give a different sound from that produced by the margin bell on the typewriter, so it may be readily distinguished therefrom. When the draw rod has been forced to the limit of its rearward movement, the projection 69 will engage the recess 67 in the small

cam 66 to hold the draw rod in said rearward position ready for the next sheet of paper.

The finger 64 is now in engagement with the groove 60 in the member 58, holding said member up, its end portion 61 having engaged the cam 70' to raise the latter and the roller arm 83 on the other side of the device. 70

The distance from the bottom of the sheet at which the gong will be sounded may be readily varied by means of the draw rod adjustment. By changing the perforation 43, which the end of the lever 51 engages, the length of the draw rod may be varied so that the lug 65 on the draw rod will be nearer or further away from the member 78 on the 75 hammer arm. The closer the lug 65 is to the member 78, the sooner the alarm will be sounded, and the larger the margin left at the bottom of the sheet. By employing a larger or smaller platen engaging cam, the 80 limits in the size of the margin may be varied. 85

If it is not desired to use the indicating device, it may be moved laterally on the rod 25 to the extreme left, where it will be in an out-of-the-way position. If it is desired to merely prevent the device from operating, the housing 91 carrying the roller 99 may be moved rearwardly until the pin 106 engages the recess 107 in the sides of the housing 95 to hold said housing in the rearward position 90 as shown by the dotted lines in Fig. 6.

The plate 92 of the housing 91 forms a guide for the upper portion of the sheet of paper and prevents it from interfering with the mechanism. The lower plate 93 serves 100 as a similar guide for the lower portion of the sheet.

It may readily be seen that by attaching the special brackets 17 with the rods 19 and 25, that the indicating device may be adapted 105 for use upon any standard make of typewriter and may be easily attached to any of the machines as they are now placed upon the market.

From the foregoing description it may be 110 seen that the improved indicating device is efficient in operation and well adapted for the purpose described.

What I claim is:

1. An indicating device for a machine having a rotatable paper holding member, comprising a frame, means in connection with said frame for detecting the passage of the end of a sheet of paper, signalling mechanism mounted on said frame and under the control of said detecting means, and attaching means to which the frame is movably connected having a portion adapted to extend beyond the sides of the machine to permit the frame to be moved to an out of the way position on the machine. 115 120 125

2. An indicating device for a machine having a rotatable paper holding member, comprising a frame, a paper engaging arm in connection with said frame, adapted to be 120 125

obstructed in its movement by the paper, a 5
slidable member in said frame, yielding means normally holding said slidale member toward the rotatable paper holding member, 10
operating means on said slidale member adapted to engage the rotatable paper holding member, means for holding said slidale member and operating means away from said paper holding member against the tension 15
of said yielding means, means between said paper engaging arm and said slidale member for releasing the latter when the bottom of the sheet of paper has released said paper engaging arm, signalling mechanism, and 20
means on the slidale member for operating said signalling mechanism when the operating member and slidale member have been moved away from the rotatable paper holding member due to contact of the operating member therewith, while the paper holding member is being rotated.

3. An indicating device for a typewriter having a platen, comprising a frame, a sheet 25
engaging arm pivoted to said frame, an operating member in connection with said frame and normally engageable with the platen, means for holding said arm in a raised position and for holding said operating member out of engagement with the platen, means operated by retraction of the platen for freeing 30
said arm to permit the same to engage the sheet, said arm upon passage of the end of the sheet being adapted to free said operating member and to cause the latter to engage the 35
platen, signalling mechanism, and means between said operating member and said signalling mechanism for operating the latter when said operating member is moved upon rotation of the platen.

4. An indicating device for a machine having a rotatable paper holding member, comprising an arm at the rear of the platen for detecting the passage of the end of a sheet 40
of paper, an operating member actuated by the rotatable paper holding member under control of the detecting arm, signalling mechanism called into operation through 45
said operating member, and a guard for said detecting arm to guide the paper both above and below said detecting arm to and from the platen.

5. An indicating device for a machine having a rotatable paper holding member comprising a pivoted arm for detecting the passage of the end of a sheet of paper, a guard 55
pivoted adjacent said arm, means on said guard engageable with the rotatable paper holding member and adapted upon retraction thereof to raise said arm to permit the paper to be moved in a reverse direction, an operating member actuated by the rotatable paper holding member under the control of the detecting arm, and signalling mechanism called into operation through said operating 60
member.

6. An indicating device for a machine having a rotatable paper holding member comprising a pivoted arm for detecting the passage of the end of a sheet of paper, a guard 70
pivoted adjacent said arm, means on said guard engageable with the rotatable paper holding member and adapted upon retraction thereof to raise said arm to permit the paper to be moved in a reverse direction, means providing for movement of said guard 75
to a position out of engagement with the rotatable paper holding member, an operating member actuated by the rotatable paper holding member under the control of the detecting arm, and signalling mechanism called 80
into operation through said operating member.

7. An indicating device for a machine having a rotatable paper holding member comprising a frame, means on said frame for 85
detecting the passage of the end of a sheet of paper, an operating member in connection with the frame actuated by the rotatable paper holding member under control of the detecting means, and signalling mechanism 90
called into operation through said operating member, said signalling mechanism comprising a support secured to the frame, a section of babbitt between said support and the frame, a gong extending from said support, and a hammer for sounding said gong. 95

8. An indicating device for a machine having a rotatable paper holding member and having a back plate comprising a frame, means in connection with said frame for detecting the passage of the end of a sheet of paper, signalling mechanism mounted on 100
said frame and under control of the detecting means, a pair of brackets attachable to the sides of the machine, and a rod connecting said brackets, the indicating device being movably connected to said rod and being positioned on the back plate of the machine. 105

9. An indicating device for a machine having a rotatable paper holding member and having a back plate comprising a frame, means in connection with said frame for detecting the passage of the end of a sheet of paper, signalling mechanism mounted on 110
said frame and under control of the detecting means, a pair of brackets attachable to the sides of the machine, and a rod connecting said brackets and extending below the back plate, the indicating device being movably connected to said rod and being positioned on the back plate of the machine. 115

10. An indicating device for a machine having a rotatable paper holding member comprising a frame, means on said frame for 120
detecting the passage of the end of a sheet of paper, an operating member in connection with the frame, actuated by the rotatable paper holding member under the control of the detecting means, and signalling mechanism 125
130

called into operation through said operating member, said signalling mechanism comprising a support secured to the frame, a section of material having tone enhancing qualities positioned between said support and the frame, a gong extending from said support and a hammer for sounding said gong.

In testimony whereof, I affix my signature.

CHARLES POKORA.
